UNITED STATES PATENT OFFICE.

WILLIAM D. GREEN, OF ARROWHEAD SPRINGS, CALIFORNIA.

FRUIT JAR.

Application filed January 20, 1922. Serial No. 530,731.

To all whom it may concern:

Be it known that I, WILLIAM D. GREEN, a citizen of the United States, residing at Arrowhead Springs, in the county of San Bernardino and State of California, have invented new and useful Improvements in Fruit Jars, of which the following is a specification.

This invention comprehends the provision of a cover for fruit jars or the like, together with adjustable means whereby the cover can be sealed with any desired degree of pressure, and the cover associated with or removed from the jar without the use of tools or other instruments.

Another object of the invention resides in the provision of a cover and fastening means therefor, which in its entirety can be removed from one jar and used in conjunction with another jar, and wherein any of the component parts of the fastening means can be replaced when desired at a very nominal cost.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views, and wherein:—

Figure 1 is a side elevation of a jar showing the subject matter of the present invention.

Figure 2 is a top plan view.

Figure 3 is an enlarged vertical sectional view taken through Figure 1.

Figure 4 is a detail view of the clamping member.

Figure 5 is a detail view of the cover.

Figure 6 is a similar view of the sectional band.

Referring to the drawings in detail, 10 indicates a fruit jar or the like of well known construction having an annular shoulder 11 surrounding the neck 12. The cover indicated at 13 is preferably constructed of aluminum and terminates to provide a flange 14 which is arranged above and in parallelism with the shoulder 11. Arranged within the cover is a disk or cork or the like 15 which separates the cover from the mouth of the jar, reposing upon the latter as illus-

trated in Figure 2. Interposed between the shoulders 11 and the flange 14 of the cover is a rubber gasket 16.

In order to clamp the cover 13 upon the jar with the desired pressure, I make use of a bar 17 which extends across the cover and is connected with the jar 10 through the instrumentality of threaded bolts or the like 18, which in turn are associated with the respective sections 19 of a sectional band which surrounds the neck of the jar immediately beneath the shoulder 11. The adjacent extremities of the band sections 19 are offset as at 20 and when arranged in face to face contact receive the offset extremity 21 of the bolts 18, said offset extremities being threaded and having associated therewith nuts 22. The bolts 18 extend upwardly from the band, and pass through openings 23 formed in the bar 17, and the extremities of said bolts are equipped with shanked nuts or the like 24. The shoulder 11 is provided with grooves 25 at diametrically opposite points to receive the bolts 18, while the flange 14 of the cover is also notched as at 26 for the same purpose.

Interposed between the cover 13 and the clamping bar 17 is a coiled spring 27, the upper end of which bears against an annular plate 28 associated with the clamping bar 17, and from which plate depends a flange 29 which surrounds the adjacent convolution of the spring. By reason of this construction, the clamping bar can be properly and easily associated with the spring, while the latter is also held properly positioned upon the collar 18 by means of a raised portion 28' formed centrally upon the cover 13 and embraced by the adjacent convolution of the spring. It is apparent that by tightening or loosening the thumb nuts 24 that the pressure upon the cover 13, may be regulated, and in addition to this fact, it is to be also noted, that the cover can be conveniently associated with the jar or removed therefrom without the use of tools of any character. In event that the jar should be broken, the cover and its fastening means in its entirety could be easily separated therefrom and used in conjunction with another jar. Anyone of the component parts can be replaced at a nominal cost at time to time as the occasion may demand.

While it is believed that from the foregoing description, the nature and advantages

of the invention will be readily apparent, I desire to have it understood that I do not limit myself to what is herein shown and described, and that such changes may be resorted to when desired as fall within the scope of what is claimed.

What I claim is:—

1. The combination with a jar having an annular shoulder, of a cover having a flange 10 arranged above the shoulder, a gasket interposed between the flange and shoulder, a sectional band surrounding the bar immediately beneath the shoulder, fastening elements detachably connecting the respective 15 sections of the band together and rising above the latter, said shoulder having grooves for the reception of the fastening elements, said flange having notches co-inciding with said grooves, a clamping bar 20 arranged above the cover and having openings for the reception of said fastening elements, a spring interposed between the bar and said cover, and winged nuts associated

with the upper ends of said fastening elements for the purpose specified. 25

2. In combination, a jar cover, a centrally raised portion formed on said cover, fastening elements arranged at the opposite sides of the jar, means connecting said elements with the jar, a clamping bar extended across the cover, and having openings for the reception of said fastening elements, a coiled spring interposed between the cover and said bar, the lower convolution of said spring embracing the said raised portion 30 of the cover, an annular plate carried by said clamping bar and against which the upper end of the spring bears, a flange depending from said plate and surrounding the adjacent convolution of the spring, and winged 35 nuts threaded on the upper ends of said fastening elements as and for the purpose specified.

In testimony whereof I affix my signature.

WILLIAM D. GREEN.
